ATTORNEY

UNITED STATES PATENT OFFICE.

HERMANN FISCHER, OF NEW YORK, N. Y.

STRING MUSICAL INSTRUMENT.

Application filed July 28, 1925. Serial No. 46,549.

The object of the present invention is to so modify the form, that is to say construction, of string instruments such as violins, cellos, and violoncellos, as to greatly improve 5 the tone and volume thereof.

The invention will be understood by reference to the accompanying drawing, in which—

Figure 1 is a plan view of a violin back, 10 illustrating in dotted lines the usual position of the area of greatest thickness, and in full lines the applicant's change in form and position thereof;

Figure 2 is a transverse sectional view on 15 the line 2—2, Figure 1.

By reference to the drawing, it will be seen that the figures therein shown are of a violin having a face A and a back B. In 20 violins as now constructed, the sound post is disposed in the exact centre, longitudinally and transversely, of the violin head, and an area surrounding the sound post is of greatest thickness in both the back and the face of the violin. This thickened area 25 is indicated by the dotted lines a, Figure 1. Such a construction, universally employed at the present time, does not enable an ideal response by the wood to the vibrations of the strings. If the wood, so constructed, acts 30 to satisfactorily transmit the high tones of the strings, it does not satisfactorily transmit the low tones of the strings. In other words, the present violin construction is such that no special provision is made for acting 35 upon the low tones of the scale in a manner different from the high tones. The sound post being disposed in the centre of an area of greatest resistance to vibration, and that area being in the exact centre of the violin 40 back, the action of the wood is the same along any lines extending regularly from the axis of said area. I have discovered that such construction is faulty in principle and effect.

In my construction I locate the sound post nearer one side of the violin than the opposite side, and below the sound post position 45 I create in the violin back a thickened area which extends longitudinally of the violin from a point above the waist to a point below the same, this area being relatively narrow and preferably forked at its ends, as 50 illustrated in Figure 1.

The dimensions shown in Figure 2 are

merely to illustrate the principle that the 55 thickened area of the violin back, and also the face if desired, is disposed to one side of the longitudinal centre of the violin, the thickness being magnified in the drawing over that of the thin area for plainness of 60 illustration. I have designated said thickened area by reference character b and the forked sections thereof by the reference character b'.

In the action of the strings upon my instrument, constructed in accordance with the drawings, the rapid vibrations of the high notes, being of relatively great force as compared with the slower vibrations of the low notes, find their proper area of reaction upon 65 the relatively narrow and therefore stiff area to the right of the sound post, Figure 1. Notes which would otherwise be damped or distorted by the fact that the distance between the sound post and edge of the violin 70 back is too great in the usual violin construction, will be ideally acted upon in said relatively stiff area. Notes which would be damped or distorted by the fact that the distance between the sound post and edge of 75 the violin of usual construction is too short for their slow vibration and low force will be ideally acted upon in the relatively wide and flexible area to the left of the sound post, Figure 1. The sound post is design- 80 ated by the reference character c.

It will be understood that various modifications may be made in the embodiment of the invention illustrated in the drawings without departing from the spirit of the 90 invention, what I claim and desire to secure by Letters Patent being as follows:—

1. A string instrument comprising a back, a face, a string support, and connecting means for the said elements, the back having 95 a thickened area disposed to one side only of its longitudinal axis, said area being relatively narrow and long, and extending parallel with said longitudinal axis both above and below the string support, as and for 100 the purpose set forth.

2. A string instrument constructed in accordance with claim 1, in which each end of the said reinforced area is forked.

In testimony whereof, I have signed my 105 name to this specification.

HERMANN FISCHER,
